[57] CLAIM

The ornamental design for a rack for cassettes and compact discs, as shown and described.

DESCRIPTION

FIG. 1 is a perspective view of a rack for cassettes and compact discs showing my new design thereof;

FIG. 2 is a top plan view thereof;

FIG. 3 is a rear elevational view, the opposite side being a mirror image thereof;

FIG. 4 is a bottom plan view thereof;

FIG. 5 is a left side elevational view, the opposite side being a mirror image thereof; and,

FIG. 6 is a cross sectional view taken along line 6—6 of FIG. 2.

The broken line showings of FIGS. 1 and 6 are for illustrative purposes only and form no part of the claimed design.
